PORTABLE LAMP

Jay Monroe, Flushing, N.Y., assignor to Tensor Electric Development Co., Inc., Brooklyn, N.Y., a corporation of New York

Continuation of design applications Ser. No. 61,152, June 29, 1960, and Ser. No. 65,532, June 9, 1961. This application June 27, 1962, Ser. No. 71,039

Term of patent 14 years

(Cl. D48—20)

FIG. 4

FIG. 5

FIG. 6

FIG. 1 is a perspective view of a portable lamp showing my new design;

FIG. 2 is a rear elevation thereof;

FIG. 3 is a bottom plan view of the reflector and a portion of its support;

FIG. 4 is a perspective view of a modified embodiment of the lamp shown in FIG. 1;

FIG. 5 is a rear elevation of the embodiment of FIG. 4; and

FIG. 6 is a top plan view of the embodiment of FIG. 4.

The sides not shown in FIGS. 1 and 4 are substantially the same in appearance as the respective sides shown.

The characteristic features of my design for a portable lamp reside in the association of the specific reflector and adjustable support therefor combined with a rectangular shaped base member substantially as shown.

This is a continuation of my copending applications Serial Nos. D. 61,152, filed June 29, 1960, for work lamp for jewelers or the like, and D. 65,532 filed June 9, 1961 for portable work lamp, and both now abandoned.

I claim:

The ornamental design for a portable lamp, as shown and described.
